SAFETY RAZOR CASE

Ralph A. Muscatiello, Norwood, Mass., assignor to The Gillette Company, Boston, Mass., a corporation of Delaware

Filed Mar. 24, 1961, Ser. No. 64,473

Term of patent 14 years

(Cl. D58—12)

FIG. 1

FIG. 3

FIG. 1 is a plan view of a safety razor case showing my new design, the transparent cover of the case being removed in this view;

FIG. 2 is a view of the case in front elevation, showing the cover in its closed position; and

FIG. 3 is a corresponding view in side elevation.

I claim:

The ornamental design for a safety razor case, as shown and described.
